UNITED STATES PATENT OFFICE.

WILLIAM J. WILSON, OF BUCKHOLTS, TEXAS.

CULTIVATOR.

1,280,610.

Specification of Letters Patent.

Patented Oct. 1, 1918.

Application filed August 13, 1917. Serial No. 185,909.

To all whom it may concern:

Be it known that I, WILLIAM J. WILSON, a citizen of the United States, and a resident of Buckholts, in the county of Milam and State of Texas, have invented a new and Improved Cultivator, of which the following is a full, clear, and exact description.

My invention relates to wheel cultivators and particularly to what is known as seat-guide cultivators in which the plow beams are guided by a lateral movement of the seat and pressure by the driver with his foot against a plow beam at the side toward which the cultivator shovels or plows are to be guided.

The general object of my invention is to provide for a better guiding of the cultivator through the movement of the seat.

A more specific object of the invention is to effect the guiding of the plows by a novel relation of the wheel frame, tongue, and the floating plow structure to one another and to the controlling seat.

The stated objects are attained by providing a tongue having a frame at its rear end so connected with the seat as to be thrown by the latter in the direction in which the plows are to be guided, the tongue frame being shiftable relatively to the wheel frame and against the same whereby to turn the wheel frame with the turning of the tongue, thereby castering the wheels, the plow beams being carried by a floating arch suspended from the wheel frame and having controlling connections with parts appurtenant to the tongue and to the wheel frame, whereby the floating plow structure will be given an accelerated movement at the forward end in addition to the direct action on the beams by the pressure of the driver's foot.

Other objects of the invention and its advantages will clearly appear as the description proceeds.

Reference is to be had to the accompanying drawings forming a part of this specification in which similar reference characters indicate corresponding parts in all the views, it being understood that the drawings are merely illustrative of one example of the invention.

Figure 1 is a plan view of a cultivator embodying my invention;

Fig. 2 is an approximately central longitudinal vertical section thereof;

Fig. 3 is a detail in transverse vertical section on an enlarged scale, the section being taken on the line 3—3, Fig. 1;

Fig. 4 is an enlarged view partly in transverse vertical section showing elements appurtenant to the ends of the floating arch;

Fig. 5 is a longitudinal vertical section on the line 5—5, Fig. 4;

Fig. 6 is a detail side view on an enlarged scale of the casting clipped to the floating arch at the center, said arch being in section;

Fig. 7 is a fragmentary transverse vertical section on the line 7—7, Fig. 1;

Fig. 8 is a fragmentary view in transverse vertical section through the wheel frame and tongue frame at the point of contact between said frames and showing the guide bracket or race for the tongue frame;

Fig. 9 is a detail in transverse vertical section given to show one of the hangers for supporting the plow lift shaft;

Fig. 10 is a fragmentary plan view of lever and link devices for giving an accelerated movement to the floating plow structure through the arch thereof;

Figs. 11 and 12 are diagrammatic plan views given to indicate the movements of the parts and to be hereinafter referred to in explaining the operation;

Fig. 13 is a fragmentary view on a reduced scale, the view being taken in a plane corresponding with the line 13—13, Fig. 1, and showing the floating arch and the manner of suspending it from the front end of the wheeled frame, parts being omitted from the view in the interest of clearness.

In carrying out the invention in accordance with the illustrated example, a wheel frame is provided, designated generally by the numeral 10, including a front cross bar in the form of an angle bar having a horizontal and a depending flange as seen best in Fig. 2, and side bars 11, there being a pair of the latter bars at each side. The side bars 11 are mounted on the axle 12 having running wheels 13, the connection with the axle being established in the illustrated

form by castings 14 rigid with the side bars and made fast in any suitable manner to the axle. In practice suitable braces are employed between the cross bar 10 and side bars 11, there being shown corner braces 15, and also, cross braces 26, 29, hereinafter referred to, or equivalent members, are employed.

Centrally on the axle 12 is secured the seat bracket 16, on a rearward extension of which is pivotally secured as by a bolt 19, a structure designated generally by the numeral 17 on which the standard or arm 18^a of the seat 18 is secured, said bolt passing through an oblong slot 19^a in bracket 16. The forward end of the bracket 16 is forked, as clearly seen in Fig. 2, and constitutes a guide for lateral movement of a frame 21 rigidly secured to the tongue 20, said frame 21 hereinafter referred to as the tongue frame is rounded at the rear end where it engages said bracket 16 and has also rounded sides to have relative movement to the side bars 11 of the wheel frame as herein-
25 after explained. The tongue frame 21 includes a plate 22 secured to said frame at the forward end and having flanges 22^a between which the tongue 20 is received. Bolts 23 secure to the tongue upper and lower strap irons 24, 25 and the rear ends of the straps are bolted as at 27 to a cross brace 26, the ends of which are secured as at 28 to the sides of the tongue frame 21. Also said plate 22 of tongue frame 21 has a boss 21^a through which one of the bolts 23 passes. In addition to the cross brace 26 there is a curved brace 29 in the tongue frame 21, said curved brace being formed in sections that overlap and are secured by a bolt 30 to the rear end of the tongue 20. The sections of the brace 29 curve rearwardly and carry shoes 31 which are grooved to receive the tongue frame 21, while permitting adjustment of said shoes on the frame as herein-
40 after explained. Bolts 32 extend through the cross brace 26 near the ends and through the members of the curved brace 29 adjacent to the shoes 31 and in order that there may be relative adjustment of these parts with
45 a movement of the shoes 31 on the tongue frame 21, a series of holes 33 are formed in the brace members 29 and a series of holes 34 in the cross brace 26. Bolts as at 31^a may be employed to secure the shoes 31 in the
50 adjusted position although it will be observed that the curved braces 29 definitely position the said shoes according to the adjustment of the said braces. When bolts are employed at 31^a a series of holes in the tongue frame 21 accommodate the bolts in the adjusted position.

The structure 17 carrying the seat 18 is in the form of an arch having a base 35 secured by the pivot bolt 19 to the casting

16, as well as side uprights 36 and a top 65 cross bar 37. Connection is established between the tongue and the structure 17 as follows: Cross braces or links 38 connect the base bar 35 with the cross bar 26 of the tongue frame 21 and cross links or 70 braces 39 connect the top bar 37 with said cross bar 26. The forward ends of the bars 38, 39 extend, respectively, to the upper and lower sides of the cross bar 26 and are secured to said bar and to one another as at 40 to permit of pivotal play. Similarly, the rear ends of the cross bars 38 are bolted as at 41 to the base bar 35 and the rear ends 43 of the cross brace 39 are hooked to extend through holes in the 80 bar 37 and threaded to receive securing nuts 44. The connection between the said structure 17 and the tongue frame 21 through the medium of the cross bars 38, 39 serves to give a lateral throw to the tongue 20 and 85 its frame 21 by a movement of the seat about the pivot 19 as will hereinafter more clearly appear. In order that a lateral movement of the tongue frame 21 may give lateral movement in a similar direction to the 90 wheel frame 10, contact of the tongue frame 21 with side bars 11 of the wheel frame is established and at the point of contact U-
95 brackets 45 are secured to the adjacent bars 11 and overlap the tongue frame 21 above and below the same as will be clear from Figs. 1 and 8.

The purpose and result of the lateral movement of the tongue frame 21 by the seat and the movement of the wheel frame 10 by the said tongue frame may best be understood after considering the floating plow structure carrying the cultivator shovels or plows as next described.

The plow beams 46 carrying plows or 105 shovels 47 in suitable numbers and positions are connected at their forward ends with a transverse floating arch designated generally by the numeral 48, each lower laterally offset end 49 of which has fitted thereon a 110 sleeve 50 concaved at its ends to correspond with cone bearings 51, 52. To the upwardly projecting ends of the bearings 51, 52 a horizontal strap 53 is secured, said strap being bent around the vertical portions of the arch 48 and extending outwardly therefrom to receive between the opposite sides of the strap the projecting ends of the bearings. The outer bearing 51 is secured by a slot and pin connection, there being a slot 54 in the strap receiving a pin 55 extending through said slot and through the upwardly projecting end of said bearing 51. At the opposite end each strap 53 is secured by a pin 55^a passing through holes in the opposite sides of the strap. The slot and pin connection 54 and 55 provides for the adjustment of the bearings 51, 52 against the sleeve 50 for tak- 120 125

ing up wear. The arch 48 is hung from the vertical member of the transverse angle bar of the frame 10 by hangers 56, the upper ends of the said hangers being laterally bent 5 to hook into the holes of the vertical flange of the frame bar and suitably secured as by a cotter pin 57 (Fig. 2), the lower ends of said hanger bars being secured as at 58 to the straps 53; the arrangement is such that 10 the hangers may swing sidewise with a lateral movement of the floating arch. To the center of the floating arch is rigidly secured in any suitable manner as by a U-bolt 59^a, (Figs. 2 and 6), a casting 59 which has at 15 its upward side upwardly projecting spaced lugs 60 that are positioned at the front and back of the vertical member of the wheel frame bar 10 to give guided movement to the arch on said frame bar. The upper terminal 20 61 of each bearing 52 embraces the vertical portion of the floating arch 48 and said terminal receives also the lower end of a rod 62. The rods 62 extend upwardly and rearwardly and their ends are upturned and pivotally secured as at 63 to the shoes 31 of the 25 tongue frame brace 29. Thus, the rod 62 effects a connection between said shoes 31 and the lateral ends of the floating arch 48, the purpose of which will appear from the 30 statement of the operation hereinafter given.

To each sleeve 50 is secured a clamp 64 by clamp bolts 65. The rear end of the clamp 64 presents jaws which are clamped by clamp bolts 66 to the pin 67 of a clevis 68 on the 35 front of the plow beam 46. The characters 52^a indicate set screws for bearings 52.

To each end 49 of the floating arch 48 is secured as at 69, the forward end of a brace rod 70, said rod having a turnbuckle 71, if 40 desired, to adjust it and having its downwardly bent rear end secured in one of a series of holes 72^a in a bracket 72 secured to the plow beam 46 by rivets 73 or other means. The connection of the plow beams 46 with the floating arch 48 through the clamps 64, and the provision of the brace rods 70, cause said floating arch and plow beams to move laterally as a rigid unit.

To connect the floating arch with the 50 draft-trees a fitting 74 is applied to each end 49 of the said arch, its forwardly extending arm 75 having an eye for engagement by a hook 76 on a short length of chain 77, the forward end of which is provided with a 55 hook 78 which may hook into any one of a vertical series of holes 79 in a vertical bar 80, the upper end of which is hung on the end of equalizer bar 81. The swingletrees 82 have links 83 or the like engaging in one or 60 other of the holes 79 above the chain 77. The equalizing bar 81 is secured by a bolt 84 to the tongue 20. Said tongue 20 adjacent to the rear of the equalizing bar 81 has an iron 85 bolted to its under side and the rear

end of said iron is flanged and carries a horizontal roller 86 which runs against the under side of the transverse front bar of the frame 10.

Plow lift means is provided on the order of what is known as a horse lift in which the 70 pull exerted by the draft animals serves to lift the plows, the said plow lift comprising the following which is a known construction. The wheel frame 10 has secured to the side bars 11 four hangers 87, 88 and said hangers provide bearings for a transverse rock shaft 89. On the shaft 89 near each end is secured a rearwardly extending arm 90 to the outer hooked end of which is secured the upper end of a chain 91, the lower end of said chain being secured on a fitting 93 secured by clamp bolts 94 or the like to each plow beam 46 so that the rocking of the shaft 89 will lift the plow beams through the medium of arms 90 and chains 91. Connection is established also between the rock shaft 89 of the plow lift and the arched axle 12 through the medium of side rods 95, the forward ends of which are connected with arms 96 on the ends of the said rock shaft, and the rear ends of which rods have connection with clips 97 secured to the axle 12 at the juncture of the upright and lateral portions thereof and embracing both to be rigid therewith. The shaft 89 is adapted to 95 be locked by a hand lever 98 rigid on said shaft and having a latch 99 engaging a rack or toothed sector 100. To regulate the depth of the plows, chains 101 are engaged at their lower ends with the eyes 92 of the clamps 93 and the upper ends of said chains are engaged by hooks 102 on levers 103, of bell crank form the ordinary latches 105 of which engage racks 104, said levers being in effect bell cranks. The levers 103 are mounted on short shafts 106 turning in bearings 107 on the castings 14 of the wheeled frame 10. The levers 103 will not be disturbed at the end of the row since they merely control the depth of the plows. To lift the plows at the 100 end of a row the lever 98 is disengaged from its rack 100 thereby leaving the shaft 89 free to rock. A forward pull on the tongue can now move the tongue and the wheel frame 105 forwardly, the pull acting on the axle at the arch while the wheels remain stationary by the action of rods 95 and arms 96, the traction of the wheels exerting a rearward pull on the arms 96, thereby rocking the shaft 89 to throw the arms 90 upwardly and through the chains 91 to exert a lift on the plow beams 46.

Referring particularly to Figs. 1 and 10 the numeral 108 indicates a lever (of the third class) fulcrumed by a pin, as 109 or 110, (either of which may be inserted as a fulcrum), on a bracket 111 on the frame bar 11 near the front end of the tongue frame 21

outside of the latter. One arm of lever 108 connects by a link 112 with one side of the tongue frame 21 while the other arm of said lever connects by a longer link 113 with the 5 casting 59 on the floating arch.

The numeral 114 indicates stirrups or foot bars on the plow beams 46 against either of which the driver may exert pressure with his foot.

10 It is to be observed that the tongue structure including the tongue proper 20 and the frame 21 is a floating structure, the same being free to float laterally by a sliding movement on the wheeled frame, since it has no 15 pivotal connection or other positive connection or restraint on the wheeled frame. The only restraint to the lateral floating movement of the tongue frame is the connection of the front end with the draft animals and 20 the lateral movement being limited by the side members of the wheeled frame.

The movements of the parts in guiding the cultivator are as follows, reference being had to the diagrammatic Figs. 11 and 25 12 in addition to the other figures showing the detail construction described. In order to guide the plows to the left, for example, in maintaining the plows in proper positions relatively to the row of plants, the driver 30 pressing his foot against the left foot bar 114 will swing the seat to the right, said seat turning with the pivot 19 as a center. This will cause the cross bars 38, 39 to swing the tongue with its frame 21 to the left. The 35 frame 21 in turn in contacting with the adjacent side bar 11 of the wheel frame at the guide bracket 45 will move the wheel frame to the left, thereby castering the wheels. In the movement of the floating tongue frame 40 to the left the tongue as a whole will have more or less movement in the same direction, the forward end tending to swing on the neck yoke connection and to whatever extent the neck yoke connection fails to hold the 45 tongue then the lateral movement of the tongue will have guiding movement on the horses in the proper direction. Since the tongue frame is floating in the wheel frame and the point of contact is at the bracket 45, 50 the forward end of the wheel frame 10 will have faster movement than the adjacent portion of the tongue, the tongue frame and wheel frame changing their relative angularity, in which movement the tongue frame 55 21 may race in the guide brackets 45. The accelerated movement of the front end of the frame, thus quickens the lateral movement of the floating plow structure in dodging a plant or obstruction. In the lateral 60 movement of the front angle bar of the wheel frame 10 it will swing the floating arch 48 to the left by the connection due to the hanger rods 56, thereby giving to the front end of the plow beams the increased

lateral movement imparted to the wheel 65 frame in addition to the positive movement of the floating plow structure by the direct pressure of the driver's foot. The whole floating plow structure being stiffened by the braces 71 and clamps 64, the right plow 70 beam responds to the movement of the left plow beam. An accelerated lateral movement of the floating plow structure is further produced by the fact that the lever 108 partakes of the movement of the bracket 111 75 on the wheeled frame which therefore bodily carries the lever 108 faster than the link 112 is moved by the tongue frame 21, the result of which is that the relatively slower speed of the link 112 holds back the adjacent 80 arm of the lever 108, thereby relatively increasing the throw of the opposite arm and causing the link 113 to increase the movement of the floating arch relatively to the tongue structure. In the lateral movement 85 of the parts to the left also, the rods 62 play a part. As will be seen from the plan view these rods are somewhat convergent toward the front and the front ends of said rods 62 move faster than the rear ends, the front 90 end of the rod 62 at the left swinging forwardly in an arc while the front end of the right hand rod 62 swings rearwardly in an arc, the result of which will be a tendency to retard the forward movement of the right 95 hand plow beam 46 while the left hand rod 62 exerts a forward thrust on the floating arch 48 and thereby tends to exert a forward pull on the left hand plow beam 46, thus contributing to the guided movement of 100 the plows. We have thus seen that all the movements contribute to quick and effective guiding of the plows, due, first, to the direct thrust on the floating plow structure by the driver; secondly by the lateral movement 105 of the tongue and its guiding effect on the horses; third, the castering movement of the wheeled frame; and fourth, the accelerated movement of the floating plow structure at the front in the proper direction. In any 110 lateral guiding action on the horses by the swinging of the tongue a further contribution is given to the guided movements by the pull of the horses through the draft trees on the ends of the floating arch through the connection with the chains 17. The angularity of the rods 62 is variable by shifting the shoes 31, and the adjustment of the same and of the curved brace sections 29 by engaging the pin 32 in one or other of the holes 33, 34, said brace sections 29 being adapted to pivot on the securing bolt 30. 115

Referring again to the adaptability of the bracket 111 and the lever 108 to receive either fulcrum pin 109 or 110, it is explained that with both of said pins in place, obviously no action of the lever is possible and this condition is produced when the culti- 120 125

vator is not in action as when going to or from the field. Also, it is observed that a forward pull on the tongue causes the tongue frame 21 to contact with the front cross bar 5 of the wheeled frame 10 while a backing movement of the tongue causes the rear end of the frame 21 to contact with the arch of the axle 12.

I wish to state in conclusion that although 10 the illustrated example constitutes a practical embodiment of my invention, I do not limit myself strictly to the mechanical details herein illustrated, since manifestly the same can be considerably varied without departure 15 from the spirit of the invention as defined in the appended claims.

Having thus described my invention, I claim as new and desire to secure by Letters Patent:

20 1. In a seat-guide cultivator, a wheeled frame, a seat pivotally mounted thereon, a floating plow structure including beams at the sides of the seat to be pressed laterally by the driver in shifting the seat, and a floating tongue structure on the wheeled frame and unconnected therewith and movable laterally by the movement of the seat and adapted to thereby impart a lateral movement to the wheeled frame.

30 2. In a seat-guide cultivator, a wheeled frame, a seat pivotally mounted thereon, a floating plow structure including beams at the sides of the seat to be pressed laterally by the driver in shifting the seat, a floating tongue structure slidable on the frame and movable laterally thereon by the movement of the seat and adapted to thereby impart a lateral movement to the wheeled frame, and means connected with the front end of the 40 floating plow structure and operable with the lateral movement of the wheeled frame and tongue structure to impart a lateral movement to the said front end of the plow structure.

45 3. In a seat-guide cultivator, a wheeled frame, a seat pivotally mounted thereon, a floating plow structure beneath said frame including plow beams adapted to be pressed laterally by the driver from the said seat, a floating tongue structure supported on the wheeled frame in position to contact therewith and move the wheeled frame laterally by a lateral movement of said tongue structure, the said wheeled frame and tongue 55 structure being relatively movable to vary their angular relation in response to pressure of the tongue structure against the wheeled frame, said seat being connected with the tongue frame to shift the said tongue frame by movement of the seat.

50 4. A seat-guide cultivator including a wheeled frame, plow means beneath the frame, a seat pivoted on said frame, and a tongue structure supported on the wheeled

frame and free to float laterally thereon at 65 its points of support and connected with said seat to respond to the movements of the latter, said tongue frame when moved by the seat being adapted to impart lateral movement to the wheeled frame. 70

5. In a seat-guide cultivator, a wheeled frame, a tongue being adapted to have lateral movement on said frame, a frame on the rear end of the tongue within the wheeled frame and having curved sides 75 adjacent to the sides of the wheeled frame to move the latter, said tongue frame being adapted to assume different angular positions relatively to the wheeled frame, means to guide the movements of the tongue frame 80 relatively to the wheeled frame, a seat pivotally mounted on the wheeled frame, means to shift the tongue frame by the movement of said seat, and a floating plow structure supported beneath the wheeled frame and 85 tongue including beams adapted to be pressed by the driver from the said seat.

6. A seat-guide cultivator including a wheeled frame, a seat pivotally mounted thereon, a floating plow structure beneath said frame including plow beams adapted to be pressed by the driver from the said seat, means operated by movement of the said seat to give a castering movement to the wheeled frame, and means operable by 90 movements of the wheeled frame and connected with the floating structure at the front thereof to accelerate the movement of the said structure.

7. In a seat-guide cultivator, a wheeled 100 frame, a seat pivotally mounted on the said frame, means to exert lateral pressure on the wheeled frame by a movement of the seat to give a turning movement to the said frame, plow beams beneath the said frame, and 105 adapted to be pressed laterally by the driver from the said seat, an arch to which said plow beams are connected, means swingably suspending the said arch from the front of the wheeled frame at each side, and 110 means connected with the arch at its approximate center and movable with the lateral movement of the front of the wheeled frame to impart a lateral impetus to the arch. 115

8. In a seat-guide cultivator, a wheeled frame, a seat pivotally mounted thereon, plow beams beneath said frame and adapted to be pressed by a foot of the driver from the said seat, an arch with which said beams 120 are connected at the front, a tongue movably mounted on the wheeled frame, a frame rigid with the tongue and adapted to contact with the wheeled frame to shift the latter, means to laterally shift the tongue 125 frame by a movement of the seat, a lever fulcrumed between its ends on the wheeled frame near the front, a link connecting one

- arm of said lever with the tongue frame, and a link connecting the other arm of said lever with the said arch.
9. In a seat-guide cultivator, a wheeled frame, a seat swingable on the said frame, a plow structure floatingly suspended beneath the wheeled frame, a tongue structure laterally movable on the wheeled frame, means to move the tongue structure by a movement 10 of the seat, and rods connected at their rear ends with the tongue structure at the sides thereof and connected at their forward ends with the floating plow structure.
10. In a seat-guide cultivator, a wheeled frame, a seat swingable on the said frame, a plow structure floatingly suspended beneath the wheeled frame, a tongue structure laterally movable on the wheeled frame, means to move the tongue structure by a 15 movement of the seat, and rods connected at their rear ends with the tongue structure at the sides thereof and connected at their forward ends with the floating plow structure, said rods being convergent forwardly; together with means to vary the relative angular position of the said rods.
11. In a seat-guide cultivator, a wheeled frame, a seat swingable on said frame, a floating plow structure suspended from said 20 frame, a tongue on the wheeled frame, a frame rigid with the tongue within the wheeled frame, shoes on the tongue frame near the rear end at the sides and adjustable thereon, means to move the tongue frame laterally by a movement of the seat, and rods connected at their forward ends with the floating plow structure and connected at their rear ends with the said adjustable shoes.
12. In a seat-guide cultivator, a wheeled frame, a seat swingable on said frame, a floating plow structure including plow 25 beams adapted to be pressed laterally by the driver from the said seat, a tongue structure on the wheeled frame adapted to have lateral movement against the wheeled frame to move the latter, and crossed elements connected with the seat and with the tongue frame.
13. In a seat-guide cultivator, a wheeled frame, a seat swingable on said frame, an upwardly extending structure rigid with the seat in front of the same to swing therewith, a tongue structure movable on the frame, 30 crossed elements pivotally connected at their front ends with the said tongue structure and pivotally connected at their rear ends with the rigid structure on the seat at the base of the latter, additional crossed elements pivotally connected with the tongue structure and pivotally connected at their rear ends with the top of the rigid structure on the seat, and a floating plow structure beneath the wheeled frame.
14. In a seat-guide cultivator, a wheeled frame, an arch floatingly suspended beneath the wheeled frame and having laterally extending members at its base, plow beams connected at their front ends with the laterally extending members of the arch, a seat 35 swingable on the wheeled frame, a tongue structure within the wheeled frame and movable laterally relatively to the latter by a movement of the seat, and rods pivotally connected with the laterally extending members of the arch and pivotally connected at their rear ends with the said tongue structure at the sides of the latter.
15. A seat guide cultivator including a wheeled frame, plow means beneath the 40 frame, a floating tongue structure supported on said frame to have floating movement laterally thereon and adapted to thereby impart a lateral movement to said wheeled frame, and a pivoted seat operatively connected with said floating tongue structure to constrain the latter to move laterally with the movement of the seat.
16. In a cultivator, a wheeled frame, an arch beneath the frame, said arch presenting 45 lateral members at the base thereof, plow beams, means connecting the forward ends of the plow beams with the said lateral members of the arch, horizontal straps on said arch approximately parallel with the laterally extending members and adjacent thereto, and hangers pivotally connected at their upper ends with the wheeled frame and pivotally connected at their lower ends with said straps.
17. In a seat-guide cultivator, an arched axle having wheels, a frame on the arch of the axle and extending forwardly, said frame having a cross bar at the front angular in cross section, presenting approximately horizontal and vertical flanges, a tongue above said bar, a roller on the tongue engaging the under side of the said horizontal flange, a frame on the tongue at the under side within the wheeled frame, said tongue frame being adapted to contact at its front end with the vertical flange of the said cross bar and adapted to contact at its rear end with the arch of the axle, a seat swingable on the arch of the axle, and connections between 50 the said seat and the tongue frame.
18. A wheeled cultivator including an arched axle having wheels, a frame on the arch of the axle and extending forwardly therefrom, and a tongue on the said frame and movable relatively thereto, a frame rigid with the tongue at the under side within the first frame, the rear end of said tongue frame being adapted to contact with the arch of the axle when the tongue is backed, and the first frame having a cross bar with which the front end of the tongue frame is 55 adapted to contact.

19. A seat guide cultivator including a wheeled frame, plow means beneath said frame, a floating tongue structure supported on said frame and adapted to impart lateral 5 castering movement thereto, said tongue frame being free to slide laterally on the wheeled frame at the points at which it is supported thereon, and a seat pivoted to have lateral movement and connected with 10 said tongue structure to slide the same laterally.
20. In a seat guide cultivator, a wheeled frame, a seat pivotally mounted thereon, a
- floating plow structure beneath said frame including plow beams adapted to be pressed by the driver from said seat, a tongue structure supported on the frame and connected with the seat to be moved laterally thereby and adapted to impart lateral movement to the wheeled frame, and means operable by 20 the lateral movements of the wheeled frame and connected with the floating plow structure to accelerate the movement of said structure relatively to the tongue structure.

WILLIAM J. WILSON.
